VALENTINE DEXHEIMER, OF MONTROSE, NEW YORK.

ICE MITTEN.

Application filed February 23, 1922. Serial No. 538,531.

To all whom it may concern:

Be it known that I, VALENTINE DEXHEIMER, residing at Montrose, in the county of Westchester, State of New York, have 5 invented certain new and useful Improvements in Ice Mittens; and I do hereby declare the following to be a full, clear, and exact description of the invention, such as will enable others skilled in the art to which 10 it appertains to make and use the same:

This invention is an improvement in ice mittens, one of the objects being to provide a simple and effective mitten to be used for domestic purposes.

15 It is well known that a cake of ice is a very elusive and disagreeable thing to handle. Everyone who has ever attempted to carry a piece of ice and deposit it in an icebox, knows that it is very difficult to grasp 20 the ice firmly and to hold it until it is safely disposed of. Furthermore, the hands, and usually the clothing become soiled during the process and the cold sensation produced by direct contact with the ice is very 25 disagreeable.

It is accordingly an object of the present invention to provide a means whereby a 30 piece of ice may be readily handled without producing the usual disagreeable consequences. The improved ice mitten consists 35 of a finger portion composed of a piece of sheet metal large enough to fully protect the fingers. The face of the finger portion is roughened in any suitable manner so that a large number of sharp projections or gripping 40 members extend out an appreciable distance from the surface of the metal. A strap or band of any suitable material is provided on the back of the finger portion, 45 this band being of the proper size to fit snugly over the backs of the fingers. To this finger portion, another piece of sheet metal is attached forming a shield for the thumb and back portion of the palm of the 50 hand. The face of this thumb portion is also provided with a large number of sharp projections or gripping members and a loop is provided on the back for securing this portion of the mitten to the thumb. The 55 two body members of the mitten are secured together preferably by a hinge, the hinge being so located that it is approximately in line with the center of the palm of the hand when the mitten is in use, so that the thumb

60 fingers. When this device is to be used the fingers are slipped through the band or loop on the back of the finger portion and the thumb is inserted in the loop on the thumb portion. For this purpose the two body members may be swung about their connecting hinge so as to lie in substantially the same plane, and the straps or bands are so placed upon the backs of these members that in this position it is a particularly easy matter to insert the fingers and thumb therein. 65 A piece of ice can then be picked up without bringing the hands directly in contact with it, and a very secure grip is obtained because of the sharp projections or gripping members, and the fact that these gripping members are so formed on the front of the body members as to provide means for engaging the block of ice while the body members are 70 substantially the same plane.

75 A block of ice is an extremely slippery object, and to prevent slipping and turning in the hands the sharp projections preferably extend to widely separated points in the faces of both portions of the device. The 80 device substantially covers the whole hand and the projections are preferably distributed over substantially the entire surface of the device, although it is not necessary that the distribution be uniform. It is advantageous, however, that the projections be relatively short so as not to sink too far into the ice and thus render it difficult to remove the mittens after the block of ice is deposited at the place desired.

85 In the form of the ice mitten which I prefer to use the upper or finger portion substantially covers the fingers and the lower or thumb portion substantially covers the palm and thumb, an extension being provided for the thumb, for example, at about 90 right angles to the hinge connecting the two portions together.

95 The device is very simple and can be adjusted on the hand in an instant. It is therefore especially adapted to be used for domestic purposes, for example, transferring ice from a dumbwaiter to an icebox.

100 An embodiment of the invention is shown in the accompanying drawing in which Fig. 105 1 is a front view of one form of the improved mitten.

Fig. 2 is a side view of the mitten shown in Fig. 1.

Fig. 3 is a front view of the preferred 110

form of mitten, this form having a larger thumb portion than that shown in Figs. 1 and 2.

Fig. 4 shows the method of using the improved mitten.

Referring to the drawing, a finger portion 1 is shown, this finger portion being attached to the thumb portion 2 by means of a hinge 3. A large number of sharp projections or gripping devices 4 are provided on the finger and thumb portions. The finger and thumb portions 1 and 2 respectively, may be made of any suitable sheet metal. The rough projections 4 may be made in any ordinary manner, such as perforating the metal from the back, the sharp edges of the perforations forming the projections. The projections extend to widely separated points in the faces of portions 1 and 2 so as to engage the block of ice at points which are at a considerable distance from one another in order to give the person a good "purchase" upon the ice block and enable him to prevent, with a minimum of effort, the slipping and turning of the block in his hands.

To the back of the finger portion 1, is attached a strap or band 5 which may be made of any suitable material, such as leather or fibrous material. This band 5 is attached to the piece 1 by rivets 6 or other suitable means. The thumb portion is also provided with a band 7 attached to the metal by means of rivets 8.

When each hand is provided with the improved mitten, a piece of ice 9 may be grasped and conveyed very easily and the difficulties usually encountered are avoided.

In Fig. 3 there is shown the preferred form of the invention wherein the lower part of the mitten is enlarged in size to substantially cover the palm of the hand and is provided with an extension 2^a of a shape to cover the thumb. In this form of the device the strap 7^a which slips over the thumb is at right angles to the strap of the upper part of the mitten and the hinged connection between the two parts of the mitten lies in line with the joints of the hand forming the knuckles, while in the first described form of the mitten the upper part of the

palm of the hand and fingers are covered by the upper part of the mitten and the hinged lower part bends with the thumb. The ice may be satisfactorily handled with either form of the device, but the last described form is more convenient to use and affords larger gripping area than the first.

I claim:

1. A device for handling ice comprising a pair of body members hinged together and provided with means for securing them to the hand, one of said members having a lateral projection adjacent the hinge for protecting the thumb, the body members having gripping members so formed thereon as to provide means for engaging a block of ice while the body members are in substantially the same plane.

2. A device for handling ice comprising a pair of body members hinged together, means on the backs of said members under which the fingers and thumb of the hand may be inserted while the members are in substantially the same plane, one of said members having a lateral projection adjacent the hinge for protecting the thumb, and gripping members so formed on the front of the body members as to provide means for engaging a block of ice while the body members are in substantially the same plane.

3. An ice mitten comprising, a sheet metal finger piece substantially covering the fingers, a sheet metal thumb piece substantially covering the palm and thumb, a hinge connecting said thumb piece to said finger piece, a plurality of sharp projections on the faces of said pieces and distributed over substantially the entire surface thereof, a strap secured to the back of said finger piece for detachably securing said finger piece to the fingers, and a second strap attached to the back of said thumb piece for detachably securing said piece to the thumb, said second strap being attached to the thumb piece in angular relation to the strap on the finger piece and to the hinge connecting said two pieces.

In testimony whereof I affix my signature.

VALENTINE DEXHEIMER.
